EGG BELT TRACK

Gerald L. Kitson, 9709 Belding Road,
Rockford, Mich. 49341

Filed Apr. 2, 1971, Ser. No. 130,861

Term of patent 14 years

Int. Cl. D15—99

U.S. Cl. D55—1 C

FIG. 1

FIG. 2

FIG. 1 is a plan view of an egg belt track embodying my new design.

FIG. 2 is an end view of the egg belt track shown in FIG. 1.

FIG. 3 is a top perspective of the egg belt track shown in FIGS. 1 and 2 with an egg belt shown in broken lines for illustrative purpose only.

I claim:

The ornamental design for an egg belt track, as shown and described.
